FLUID PRESSURE PRODUCING DEVICE

Filed July 21, 1943

UNITED STATES PATENT OFFICE

2,410,169

FLUID PRESSURE PRODUCING DEVICE

Ludger E. La Brie, Detroit, Mich., assignor to
 Hydraulic Brake Company, Detroit, Mich., a
 corporation of California

Application July 21, 1943, Serial No. 495,638

6 Claims. (Cl. 60—54.6)

1

This invention relates to fluid pressure braking systems, and more particularly to fluid pressure producing devices therefor.

The invention comprehends a fluid pressure producing device including a low pressure producing means, an intermediate pressure producing means and a high pressure producing means, and means operative upon attainment of a predetermined pressure in the low and intermediate pressure producing means respectively for transferring the load or pressure respectively from the low to intermediate to high pressure producing means.

An object of the invention is to provide a fluid pressure producing device operative to increase the fluid pressure through several stages without increasing the applied operating force.

An object of the invention is to provide a fluid pressure producing device operative to effect a transition from low to high pressure without perception to the operator.

Another object of the invention is the provision of a fluid pressure producing device including a low pressure producing means, an intermediate pressure producing means, and a high pressure producing means.

A further object of the invention is to provide a fluid pressure producing means including a low pressure chamber, an intermediate pressure chamber and a high pressure chamber, pistons reciprocable in the respective chambers, and means in the pistons for controlling the transition of pressure from the low to the high pressure chamber.

A still further object of the invention is to provide a fluid pressure producing means including a cylinder having small, intermediate, and large diametral bores, a piston in the cylinder having heads reciprocable in the respective bores for producing various stages of fluid pressure, and a valve system in the piston adapted to be actuated by the fluid pressure developed in the respective bores.

Other objects and advantages of the invention will appear from the following description taken in connection with the drawing forming part of this specification, and in which—

Fig. 1 is a diagrammatical illustration of a fluid pressure braking system embodying the invention;

Fig. 2 is a vertical sectional view of a fluid pressure producing device; and

Fig. 3 is a sectional view of a modified form of valve system embodied in the fluid pressure producing device.

2

Referring to the drawing for more specific details of the invention, 10 represents generally a fluid pressure producing device including a cylinder 12 adapted to be mounted in a fixed position. The cylinder 12 has one end open and its other end closed as by a head 14 having secured thereto concentric cylinders 16 and 18 providing in conjunction with cylinder 12 large, intermediate and small chambers 20, 22, and 24, respectively. Cylinder 18 includes a head 26 provided with a discharge or outlet port 28 communicating with chamber 24.

Affixed to the cylinder 10 is a suitable connection 30, normally connected to a conventional fluid reservoir or tank 32 including a passage 34 and a chamber 36 providing communication between the reservoir and chamber 20 by way of passages 38 and 40 in the wall of cylinder 12.

A piston 42 reciprocable in the chamber 20 is held against displacement by a retaining ring 44 secured to the open end of the cylinder 12. The piston includes a head 46, a reduced body portion 48 providing in conjunction with the wall of the cylinder 12 an annular chamber 50, an internal body portion 52, and a skirt 54 supporting a sealing cup 56 for inhibiting seepage of fluid from the cylinder past the piston, and arranged in the back of the piston is a socket 58. Chamber 50 communicates through passage 38, chamber 36 and passage 34 with reservoir 32.

The body portion 52 of the piston 42 has therein inter-communicating chambers 60 and 62 communicating with chamber 50 through a passage 64, and with chamber 20 by way of restricted passages 66 and 68. The communication between chambers 60 and 62 is controlled by a spring-pressed ball check valve 70 adapted to be actuated by a spring-pressed slide valve 72 reciprocable in chamber 62.

Valve 72 includes a projection 74 for association with valve 70, a projection 76 extended through and beyond a bore 78 in body portion 52 of piston 42, the purpose of which will hereinafter appear, and an annular section 80 having a plurality of passages therethrough for control of passage 68.

The head 46 of piston 42 has a plurality of ports or passages 82 therethrough providing communication between the annular chamber 50 and that portion of the large chamber 20 forward of the head 46, and a sealing cup 84 is seated on the head for control of the passages.

A piston 86 includes heads 88 and 90 adapted for reciprocation in the respective chambers 22 and 24. Piston 86 has a body portion 92 tele-

scoping the body portion 52 of piston 42 and is loosely coupled therewith to permit free self-alignment of the pistons in the respective chambers in which they reciprocate. A lock-screw 94 threaded in the body portion 92 of piston 86 inhibits relative axial movement between pistons 42 and 86. The head 88 of piston 86 has a plurality of passages 96 providing communication between chambers 20 and 22, and a sealing cup 98 is seated on the head for control of the passages.

Piston 86 has in its body intercommunicating chambers 100 and 102 corresponding to chambers 60 and 62 in piston 42. Chamber 100 is closed at one end by a ring 104 threaded in the body of the piston 86. The ring 104 receives and supports the projection 76 of valve 72 for reciprocation in chamber 100 and has in its wall a passage 106 providing in conjunction with a passage 108 in the body portion 52 of piston 42 communication between chambers 62 and 100.

The communication between chambers 100 and 102 is controlled by a spring-pressed ball check valve 110 adapted to be actuated by the fluid pressure chamber 22 and also by a spring-pressed slide valve 112 mounted for reciprocation in the chamber 102. The valve 112 includes a plunger 114 fitted in a bore 116 in the head 90 of the piston 86. A restricted passage 118 and a passage 120 provide communication between chambers 22 and 102, passage 120 being controlled by the plunger portion of valve 112. The plunger 114 of valve 112 has passages 122 through its body providing communication therethrough between passage 120 and the chamber 102.

The head 90 of the piston 86 has a plurality of passages 124 therethrough providing communication between the chambers 22 and 24, and a sealing cup 126 seated on the head controls the passages 124, the central portion thereof being adapted to abut the plunger 114 of valve 112.

A spring 128 interposed between the sealing cup 126 and the head 26 of the cylinder 18 serves to hold the sealing cup against displacement and also to return the pistons 42 and 86 to their retracted positions. Ports 130 and 132 in the walls of the respective cylinders 16 and 18 provide communication respectively between the chambers 20 and 22, and 22 and 24 when the pistons are in retracted position.

A fluid pressure delivery pipe or conduit 134 connected to the discharge port 28 of the cylinder 12 has branches connected respectively to fluid pressure actuated motors 136, preferably arranged in pairs, one pair for actuating the brakes associated with the front wheels of a vehicle, and another pair associated with the brakes of the rear wheels of the vehicle.

The brakes, which may be of any desirable type, preferably include a fixed support or backing plate 138 adapted to be secured to an axle or axle housing, a rotatable drum 140 associated with the backing plate adapted to be secured to a wheel, a pair of friction elements or shoes 142 pivoted on the backing plate for cooperation with the drum, a retractile spring 144 connecting the shoes, and a motor corresponding to the motors 136 mounted on the backing plate between the shoes and operative to actuate the shoes into engagement with the drum against the resistance of the retractile spring.

The socket 58 receives one end of a thrust rod 146, the other end of which is connected by a clevis 148 to a foot pedal lever 150 rockable on

a stub shaft 152 and connected by a retractile spring 154 to a fixed support 156.

In a normal operation, upon depressing the foot pedal lever 150, force is transmitted therefrom through the rod 146, resulting in advancing the pistons 42 and 86 on the compression stroke. During the initial movement of the pistons, the sealing cup 84 on the head 46 of piston 42 closes the passage 48, the sealing cup 98 on the head 88 of the piston 86 closes off ports 130, the sealing cup 126 on the head 90 of the piston 86 closes off port 132, and thereafter, as the pistons advance on the compression stroke, a large volume of fluid is displaced from the low pressure chamber 20 through the passages 96 in the piston head 88, past the sealing cup 98 into the intermediate pressure chamber 22, through the passages 124 on the piston head 90, past the sealing cup 126 into the high pressure chamber 24, thence through the discharge port 28 and fluid pressure delivery pipes 134 into the fluid pressure actuated motors 136, causing energization of the motors with the resultant actuation of the friction elements 142 into engagement with the drum 140 against the resistance of the retractile spring 144, to take up the clearance between the friction elements and drum. Because of the displacement of a large volume of fluid, at a relatively low pressure, the friction elements are moved into engagement with the drum quite rapidly.

After a predetermined pressure has been reached in the chamber 20, say, approximately 30 pounds per square inch, the pressure in chamber 20 acting on the ball valve 70 by way of restricted passage 66 and chamber 62 cracks the valve to thereby relieve pressure from chamber 20.

The fluid pressure in the large chamber 20 is thus relieved and a portion of the fluid is returned from the chamber through restricted passage 66, chambers 62 and 60, passage 64, chamber 50, passage 38, chamber 36, and passage 34 to the reservoir 32.

Concomitantly therewith, and upon further advance of the pistons, additional pressure will be developed in the intermediate pressure chamber 22, with the consequent displacement therefrom of fluid under pressure through passages 124 in the piston head 86, past sealing cup 126 into chamber 24, thence through the discharge port 28 and fluid pressure delivery pipes into the fluid pressure actuated motors 136, causing further energization of the motors with a resultant actuation of the friction elements 142 into engagement with the drums to provide for greater retardation of the drums 140.

Upon the attainment of a predetermined pressure in the intermediate pressure chamber 22, say, approximately 60 pounds per square inch, the ball check valve 110 will be lifted from its seat and thus provide for relief of pressure from chamber 22 through restricted passage 118, chambers 100 and 102, passage 106, passages 108, the passages in valve 72, chamber 62, past the valve 70, chamber 60, passage 64, chamber 50, passage 38, chamber 36, and passage 34 to the reservoir 32.

Simultaneously with the cracking of valve 110 providing for relief of pressure on the fluid in chamber 22, the pressure is received on the head 90 of the piston 86, and subsequent further movement of the pistons 42 and 86 produces the high pressure stage of operation of the unit by the development of high pressure on the fluid in chamber 24 with the consequent displacement

therefrom through port 28, delivery pipes 134 into the fluid pressure actuated motors 136, causing still further energization of the motors with the resultant actuation of the friction elements into further engagement with the drums to thereby inhibit rotation of the drums.

Upon attainment of a predetermined pressure, say 70 pounds per square inch, in chamber 24, acting upon the sealing cup 126, the valve 112 reciprocable in chamber 102 is moved against the 10 resistance of the valve spring to thus abut ball valve 110, which in turn abuts the projection 76 of slide valve 72, causing movement of the valve 72 against the resistance of its spring, whereby projection 74 of the valve abuts ball valve 70 to retain it from its seat. With the movement of the slide valves 72 and 112 from their normal positions, the passage 68 in the piston 42 and the passage 120 in the piston 86 are uncovered to thereby provide for more complete relief of pressure from chambers 20 and 22 through the various interconnected chambers and passages to the reservoir 32. The movement of valve 80 is insufficient to close the restricted passage 66. The complete relief of pressure in chambers 20 and 22 25 provides for the removal of parasitic load on the head 46 of the piston 42 and the head 88 of the piston 86 during the high fluid pressure development stage of operation.

Upon completion of a braking operation, the 30 foot pedal lever 150 is released and is returned to its retracted position under the influence of the retractile spring 154. This movement of the foot pedal lever retracts the rod 146 with the resultant release of the pistons 42 and 86 and return thereof to retracted position under the influence of retractile spring 128.

As the pistons return to retracted position, the valves 70, 72, 110, and 112 also return to retracted position, and simultaneously therewith a partial vacuum is created in chamber 24, resulting in drawing fluid from the reservoir through passage 34, chamber 36, and passage 38, into the annular chamber 50, thence through the passages 82 in the head of the large piston 42, past the sealing cup 84, into chamber 20, through the passages 96 in the head 88 of piston 86, past the sealing cup 98, into chamber 22, through the passages 124 in the head 90 of piston 86, past the sealing cup 126, into the small chamber 24, completely filling the chambers 20, 22, and 24.

During this operation fluid is returning to the chamber 24 from the fluid pressure actuated motors 136 and the fluid pressure delivery pipes 134 connecting the motors to the chamber 24. This may result in the chamber 24 receiving a quantity of fluid in excess of its capacity and in this event the excessive quantity of fluid is displaced therefrom through the port 132 into the intermediate chamber 22, through port 130, into the large chamber 20, and thence through passage 40, chamber 36, passage 34, into the reservoir 32.

A modification of the valve system is illustrated in Fig. 3 wherein a piston 242 includes a body portion 252 having therein intercommunicating chambers 260 and 262 communicating with a chamber 220 by way of a restricted passage 266. The communication between the chambers is controlled by spring pressure ball check valve 270.

A piston 286 has a body portion 292 telescoping the body portion 252 of piston 242, and provides within the body portion intercommunicating chambers 300 and 302 corresponding to chambers 260 and 262 in piston 242. Chamber 300 is

closed at one end by a ring 304 threaded in the body of piston 286 having a passage 306 in its wall and providing in conjunction with a passage 308 in the body portion 252 of the piston 242 communication between chambers 262 and 300.

The communication between chambers 300 and 302 is controlled by a spring-pressed ball check valve 310 adapted to be actuated by a spring-pressed valve 312 mounted for reciprocation in chamber 302. A restricted passage 316 in the piston 286 provides communication between the chambers 222 and 302.

The mode of operation of the modification is substantially identical to that of the preferred embodiment, the only difference being in the absence of the slide valve operation between the ball valves—hence needs no explanation.

While this invention has been described in connection with certain specific embodiments, the principle involved is susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is:

1. A fluid pressure producing device having a low pressure chamber, an intermediate pressure chamber and a high pressure chamber, a piston having heads movable in the respective chambers for creating pressure, and a loaded valve mechanism in the piston controlled by the differential of fluid pressure between the low and intermediate chambers for relieving the pressure in the intermediate pressure chamber to thereby transfer the load from the low and intermediate to the high pressure piston head.

2. A fluid pressure producing device having a low pressure chamber, an intermediate pressure chamber and a high pressure chamber, and a piston having heads movable in the respective chambers for creating pressure, and a valve mechanism comprising a pair of ball valves and a pair 45 of slide valves actuated by the fluid pressure in the chambers for consecutively relieving the pressure in the respective low and intermediate pressure chambers during a pressure creating movement of the piston.

3. A fluid pressure producing device comprising a reservoir, a low pressure chamber, an intermediate pressure chamber and a high pressure chamber, a piston having heads movable in the respective chambers for creating pressure, and 55 valves controlling passages through the pistons connecting the pressure chambers and reservoir, said valves being normally closed the valve between the low pressure chamber and the reservoir being first opened by a predetermined pressure in

60 the low pressure chamber, the valve between the intermediate chamber and the first chamber being first opened by a predetermined differential of pressure between the intermediate pressure chamber and the low pressure chamber, and 65 means to mechanically hold said valves open upon a predetermined differential between the high pressure chamber and the intermediate pressure chamber.

4. A fluid pressure producing device comprising 70 a reservoir, a low pressure chamber, an intermediate pressure chamber and a high pressure chamber, a piston having heads movable in the respective chambers for creating pressure, said low and intermediate chambers communicating 75 with the reservoir by way of restricted passages

in the piston, and loaded valves in the communication normally closing off communication, one of said valves being exposed on one side to the pressure of the low pressure chamber and on the other side to the pressure of the intermediate pressure chamber.

5. A fluid pressure producing device having a low pressure chamber, an intermediate pressure chamber and a high pressure chamber, a piston having heads movable in the respective chambers for creating pressure, a check valve past which said low pressure chamber communicates with the reservoir, a slide valve controlling one restricted passage from said intermediate pressure chamber to the reservoir by way of said check valve-controlled passage and said slide valve-controlled passage, said check valve normally closing the communication and adapted to be fluid pressure actuated to provide for relief of pressure from the respective low and intermediate pressure chambers.

6. A fluid pressure producing device having a

low pressure chamber, an intermediate pressure chamber and a high pressure chamber, a piston having heads movable in the respective chambers for creating pressure, said low and intermediate pressure chambers communicating with the reservoir, and a mechanism in the piston comprising a ball valve adapted to be actuated by the pressure in the low pressure chamber, a ball valve adapted to be actuated by the pressure in the intermediate pressure chamber, a slide valve between the ball valves adapted to be actuated by the movement of the second-mentioned valve, and a slide valve adapted to be actuated by the pressure in the high pressure chamber, said first-mentioned ball and slide valves operable to control the communication between the low pressure chamber and the reservoir, and said second-mentioned ball and slide valves operable to control the communication between the intermediate pressure chamber and the reservoir.

LUDGER E. LA BRIE.
